UNITED STATES PATENT OFFICE.

MAURICE F. CARRIGAN, OF MILWAUKEE, WISCONSIN.

CREAM-SEPARATOR.

No. 866,190.

Specification of Letters Patent.

Patented Sept. 17, 1907.

Application filed January 19, 1906. Serial No. 296,811.

To all whom it may concern:

Be it known that I, MAURICE F. CARRIGAN, a citizen of the United States, residing at the city of Milwaukee, county of Milwaukee, and State of Wisconsin, have invented new and useful Improvements in 'Cream-Separators, of which the following is a specification.

My invention relates to improvements in cream separators and it pertains more especially to the peculiar construction and relative arrangement of the liner plates and the vertical standards by which such liner plates are connected together, whereby said parts may, if desired, be separated from each other and removed from the receptacle, and, whereby, when in operation, the action of the apparatus may be accelerated. It is also a known fact that a vessel with a smooth interior surface may be revolved rapidly without communicating the same speed to its liquid contents.

The object of my invention is among other things, first, to so construct the operative mechanism of my device that the maximum speed of the receptacle will be communicated to its contents; second, to so construct the standards and liner plates that when connected together they will mutually support each other in position for use, and that when not in use they may, if desired, be readily separated from each other and removed from the receptacle.

The construction of my invention is explained by reference to the accompanying drawings in which, Figure 1 is a vertical section of the revoluble receptacle in which is shown a side view of the liner plates and the vertical standards by which such liner plates are connected together. Fig. 2 is a top view of the upper conical liner plate of the series in connection with the vertical standards by which the liner plates of the series are connected together. Fig. 3 is a bottom view of the lower liner plate of the series shown in Fig. 1, and Fig. 4 is a vertical section of the series of liner plates and vertical standards showing one manner of connecting such parts together.

Like parts are identified by the same reference characters throughout the several views.

1 represents a revoluble receptacle of ordinary construction which is adapted to be used in connection with the ordinary driving mechanism of a cream separator by which a rapid rotary movement is communicated to the same.

My invention consists more especially, as previously indicated, of the construction and arrangement of the series of conical shaped liner plates 2, 2 and the vertical standards 3, by which such liner plates are connected together. The vertical standards 3 are preferably secured at their lower ends to the lower conical liner plate 4 of the series, whereby they are retained in their proper relative position to each other in the inclosing receptacle. When the standards 3 have been

thus secured to the lower liner plate 4 each succeeding liner plate 5 above the first may be secured in place thereon by simply placing the same one above another within said standards, said liner plates 5 being respectively provided with a plurality of recesses 6 at their peripheries for the reception of the respective standards with which they register whereby when said liner plates are in place they will be caused to revolve with and maintain the same relative position to each other. The lower side of the several liner plates are preferably provided with downwardly projecting flanges or shoulders 7 located at short intervals apart by which said liner plates are supported from each other one above another at the proper relative distances 70 apart. While I have shown the flanges 7 formed of separate pieces and secured to said liner plates said flanges may, if desired, be formed integrally with the liner plates 6 so as to perform the same functions, it being obvious that any other means for supporting said liner plates one above another at a required distance apart may be substituted for the flanges shown.

To provide for binding the upper ends of the several standards 3 in their proper relative position around the longitudinal center of the receptacle, I preferably provide the upper conical liner plate 8 with apertures 9 formed back from the lower edge of said liner plates for the reception of the upper ends of said standards which are inserted through said apertures, whereby it is obvious that the lower wall of said apertures will 85 serve as a retaining bearing for the upper ends of said standards and prevent the liability of such standards being thrown outwardly by the centrifugal action of the device or from any other cause.

It will of course be understood that the upper end 90 of said standards are necessarily cut away so that the protruding end 10 of said standards will be of less width than the lower portion thereof and will be free to pass through the aperture 9 formed in the upper liner plate.

While I have, for convenience of illustration, shown the several liner plates of the series located at considerable distances apart, experience has demonstrated that the action of the separator may be accelerated by greatly increasing the number of liner plates 100 in a given space and for the best work the liner plates are preferably located within about one-sixteenth of an inch of each other.

It will be understood that by the construction shown, the vertical standards 3 located as they are 105 near the exterior walls of the receptacle will, as the receptacle is rapidly revolved, cause the contents to be revolved therewith, while it is obvious that were such standards dispensed with the receptacle might be rapidly revolved without causing its contents to 110 revolve with it at the same speed; that owing to the fact that the standards 3 are located in close proximity

22

to the walls of the receptacle, the contents of the receptacle is necessarily caused to revolve at substantially the same speed as the receptacle itself, whereby a rapid rotation is communicated to the milk and the separation of the cream from the milk is greatly accelerated. It will also be obvious that when desirous to remove the liner plates for the purpose of cleansing or repairing the same this object can be readily accomplished by first removing the cover 11 from the receptacle 1 when the liner plates and supporting standards may be removed together. This being done the several liner plates may be successively withdrawn from the vertical standards and separated from each other. It will also be understood that the milk which is thrown by the centrifugal action of the device against the exterior walls of the receptacle will enter the lower ends of the several ducts 12 when it will be free to pass from the receptacle therefrom through the outlet 13 of said ducts while the cream or lighter products being acted upon will pass out through the upper duct 14 when the separation is complete. The duct 14 through which the cream escapes is provided with a screw threaded stopper 15, which is supported in screw threaded bearings in the walls of the duct and serves to regulate the discharge of cream from the separator. When the duct is opened a large percentage of milk will escape with the cream. When, however, it is partially closed, a higher percentage of cream will escape.

30 The vertical standards 3 preferably extend upward so as to contact with the cover 11, whereby when the cover is in place it will bear upon the upper ends of said standards and facilitate holding said standards and liner plates theron rigidly in place within the receptacle. The cover 11 is also preferably provided with a plurality of downwardly projecting lugs 16 which are adapted as the cover is secured in place to bear upon the upper edge of the upper liner plate and serve to bind said liner plates in their proper relative position to each other and their supporting standards.

40 17 is an inlet tube which communicates from the top of the cover 11 through the central apertures 18 of the several liner plates and is connected at its lower

end to the upper end of the spindle 19 by screw threaded bearings. The upper end of said duct 17 is provided with a radial flange 20 which bears upon the upper end of said cover, whereby as said duct 17 is turned down upon the upper end of said spindle it serves to bind all of said co-operative parts together including the vertical standards, the liner plates supported thereon, the spindle and inclosing receptacle. The lower end of the duct 17 is provided with a plurality of apertures 21 through which the milk escapes from said duct into the inclosing receptacle below the lowest liner plate of said series.

55 Having thus described my invention what I claim as new and desire to secure by Letters Patent is,

1. In a cream separator the combination of a revoluble receptacle, a plurality of vertical standards arranged in a circular series around a common center within and in close proximity to the vertical inclosing wall of said receptacle, a series of conical shaped liner plates provided with a plurality of flanges by which they are supported one above another from each other, the lower liner plate of said series being rigidly connected with the lower end of said standards and each succeeding liner plate above the lower being detachably supported by said flanges from each other around said standards.

2. In a cream separator of the class described the combination of a revoluble receptacle, of a plurality of vertical standards arranged in a circular series around a common center in close proximity to the vertical walls of said receptacle, a plurality of flanges interposed between and adapted to support said liner plates one above another at slight distances apart around said standards, the lower end of said standards being rigidly affixed to and supported from the lower liner plate while the upper ends of said standards have contact bearings against the cover of said receptacle, each successive liner plate between the lower and upper one being provided with a plurality of recesses for the reception of said standards, the upper liner plate of said series being provided with apertures for the reception of the upper ends of said standards whereby when said upper liner plate is in place the upper ends of said standards will be secured together by said liner plates.

70 In testimony whereof I affix my signature in the presence of two witnesses.

MAURICE F. CARRIGAN.
